GARMENT HANGER

Clarence E. Kennedy, Pampa, Tex.

Application July 29, 1937, Serial No. 156,410

6 Claims. (Cl. 223—88)

The present invention relates to garment supports, and more particularly to improved means for firmly and securely supporting one or more garments on a hanger without danger of wrinkling, creasing, or otherwise marring the same.

An important feature of the invention consists in providing a light, efficient, and inexpensive garment hanger having a horizontally disposed supporting member or bar provided with means to prevent garments from slipping off the hanger. Additionally, the supporting member is formed to provide garment protecting means which insures one or more garments being carried on the hanger without being wrinkled or creased.

A further object consists in positioning beneath the hook of the hanger, means which permits the carrying of a loaded hanger without taking hold of the garments on the hanger or the hook so that the hanger may be carried, or connected to, or removed from, a suitable support without soiling or wrinkling the garments.

Other objects and advantages of the invention will become apparent from the following description, taken in conjunction with the accompanying claims and drawing.

Referring to the drawing, in which is shown a preferred embodiment of the invention, Figure 1 is a front elevation of my improved hanger.

Figure 2 is a sectional view taken substantially on the line 2—2 of Figure 1, and

Figure 3 is an end view of Figure 1.

While the hanger may be made of any suitable material of sufficient strength and rigidity to support the type of garment to be carried thereon without deforming any parts of the hanger, I have, for the purpose of illustration, shown it made of a single wire rod which is initially bent to form the hook 10. One end of the hook terminates in the shank 11 which is curved at 12. The lower end of the curved portion 12 projects outwardly to form the downwardly inclined arm 13, bent as at 14, to provide the horizontal supporting member or bar 15. The opposite end of the horizontal member 15 is bent upwardly, as at 16, to form the inclined arm 17 corresponding in length to the arm 13. The arm 17 terminates in a curved portion 18, which has its end twisted as at 19, about the shank 11. Manifestly, the hanger instead of being formed from a single length of wire, may be composed of several pieces or of other suitable material.

The curved portions 12 and 18 coact to provide an opened loop 20 positioned beneath the

hook 10, which imparts a certain degree of resiliency to the inclined supporting arms 13 and 17. The loop 20 also constitutes a hand engaging portion, which permits the carrying of loaded hangers without the necessity of taking hold of the garments carried by the inclined arms 13 and 17, or the hook 10. It will be seen that as the hook 10 is free, the hanger may be conveniently carried by the loop 20 without soiling or creasing the garment on the hanger, and that the hook 10 may be readily attached to, or removed from, a suitable support such as a pole, nail, or the like.

The horizontal supporting bar 15 is preferably bent to provide alternately opening loops or crimped portions 21, which may progressively decrease in width from the center of the bar 15 to its ends so as to constitute a supporting surface, which prevents garments carried thereon, such as trousers and the like, from slipping off the hanger or sliding longitudinally on the bar. Additionally, each of the loops 21 is bent medially and transversely of its width to provide on its upper surface a rounded portion 22 (Figure 3) and outwardly diverging sides or arms 23 and 24, which progressively increase in length from the ends of the rod 15 toward the center thereof. It will be seen that the rounded top portions 22 of the loops coact with the inclined sides 23 and 24 to constitute a substantially inverted V-shaped supporting surface in cross section, which has its sides of less length at the ends than at the center. The loops 21 are of such length and width that the top 22 coacts with the inclined sides 23 and 24 to provide a supporting surface which, when the garments, such as trousers or the like, are carried thereon, will prevent wrinkling or creasing of the garments and thus obviate the necessity and expense of using separate protectors for each of the garments on the hanger.

I have found that if the loops or crimps 21 are flat and not sufficiently spaced from one another, they will not effectively prevent creasing or wrinkling of the garments supported thereon. Accordingly by arranging the horizontal bar 15 with rounded or inclined supporting surfaces of the proper length and inclination, means are provided for insuring one or more garments being suspended by the hanger without danger of the garments being wrinkled or otherwise marred.

It is customary for cleaning and pressing establishments, when delivering garments, to suspend one or more of the garments on a hanger, and when such hangers are in transit or are not

properly carried, there is the liability of the garments being wrinkled or falling off of the hanger. By reason of the present invention, a built-in garment protector is provided which will insure 5 one or more garments being firmly carried by the hanger without danger of falling off and without requiring a separate protector for each garment. Further, the particular formation of the supporting rod 15 insures the garments being 10 maintained on the hanger free from being wrinkled or otherwise marred, irrespective of the position of the hanger or of any movement that might be imparted to the hanger. By reason of the opened loop formed between the hook and the 15 inclined supporting arms 13 and 17, means are provided for carrying the hanger without engaging the hook, so that the latter may be free to be attached to, or removed from, its support, without the touching of the garment carried by 20 the supporting arms 13 and 17.

It will be noted that the rounded portions 22 of each of the curved loops constitute a substantially horizontally disposed top supporting surface, which, due to the reduced taper of the 25 loop portions from the center of the rod, acts to provide additional reinforcement for the garment where the weight and pressure are the greatest, and also insures the garment being properly carried by the hanger without danger of being wrinkled, creased, or otherwise marred.

It is to be understood that the form of the invention shown and described is merely illustrative of a preferred embodiment, and that such changes may be made as fall within the purview 35 of one skilled in the art without departing from the spirit of the invention and the scope of the appended claims.

I claim:

1. A hanger of the class described having a 40 substantially horizontally disposed supporting member, said member being provided with alternately opened transversely arranged loop portions bent medially of their width to constitute a rounded top surface and downwardly inclined 45 arms, whereby a garment carried by the supporting member is prevented from falling off or from being wrinkled.

2. A hanger of the class described having a substantially horizontally disposed supporting 50 member, said member being provided with alternately opened transversely arranged loop portions bent medially of their width to constitute a rounded top surface and downwardly inclined arms, the width of said loop portions progressively decreasing from the center of the horizontal 55 member to its ends, whereby a garment carried by the supporting member is prevented from falling off or from being wrinkled.

3. A one-piece wire hanger of the class described, including spaced inclined arms having a medially disposed hook at their upper ends, said arms being connected at their lower extremities by a substantially horizontally disposed member 5 having alternately opened transversely arranged loop portions bent medially of their width to constitute a rounded top surface and downwardly inclined arms, whereby a garment carried by the supporting member is prevented from falling off 10 or from being wrinkled.

4. A one-piece wire hanger of the class described, including spaced inclined arms having a medially disposed hook at their upper ends, said arms being connected at their lower extremities 15 by a substantially horizontally disposed member having alternately opened transversely arranged loop portions bent medially of their width to constitute a rounded top surface and downwardly inclined arms, the width of the inclined arms 20 progressively decreasing from the center of the supporting member to its ends, whereby a garment carried by the supporting member is prevented from falling off or from being wrinkled.

5. A one-piece wire hanger of the class described, 25 including spaced inclined arms having their upper ends terminating in an opened loop, a hook extending upwardly from said loop, said inclined arms connected at their lower extremities by a horizontal member having alternately 30 opened transversely disposed loop portions bent medially of their width to constitute a rounded top surface and downwardly inclined arms, whereby a garment carried by the supporting member is prevented from falling off or from 35 being wrinkled, said opened loop constituting a handle to permit carrying a loaded hanger without touching the garments thereon or said hook.

6. A one-piece wire hanger of the class described, including spaced inclined arms having 40 their upper ends terminating in an opened loop, a hook extending upwardly from said loop, said inclined arms connected at their lower extremities by a horizontal member having alternately 45 opened transversely disposed loop portions bent medially of their width to constitute a rounded top surface and downwardly inclined arms, the width of the inclined arms progressively decreasing from the center of the supporting member to 50 its ends, whereby a garment carried by the supporting member is prevented from falling off or from being wrinkled, said opened loop constituting a handle to permit carrying a loaded hanger without touching the garments thereon or said 55 hook.

CLARENCE E. KENNEDY.
